APPARATUS FOR THAWING WATER
HYDRANTS OR THE LIKE

James G. Griffiths, New Kensington, Pa., assignor of one-half to E. P. Mellon II, Pittsburgh, Pa.

Application March 28, 1938, Serial No. 198,598

2 Claims. (Cl. 138—35)

The present invention relates to apparatus for thawing fire hydrants, curb boxes, gate valves, water pipes and the like, which are liable to become frozen during cold weather. The invention is particularly applicable for incorporation in fire engines and the service trucks of water companies.

It is an object of the invention to provide apparatus for thawing fire hydrants, water pipes and the like which may be used in conjunction with the usual service motor truck or fire engine.

A further object is the provision of apparatus for use in conjunction with an internal combustion engine for thawing frozen fire hydrants and valves which is readily available for emergency use, and utilizes the high temperature exhaust gases of the internal combustion engine for melting the ice.

According to the present invention, I thaw water hydrants, curb boxes and the like by directing the exhaust gas from an internal combustion motor, preferably a gasoline motor, against or around the frozen apparatus. This is accomplished preferably through a hose connected between the gasoline motor exhaust manifold and the muffler and directed into the fire hydrant casing, whereby the hot gases are directed against the frozen portion to readily melt the ice. The hose may discharge near the top of the hydrant casing, or the hose may extend down near the bottom of the hydrant casing, provision being made for the escape of gases from the hydrant at the connection to prevent back firing of the motor.

In the preferred apparatus, I provide a valve of any suitable construction intermediate the exhaust manifold and the muffler of an automobile, and a conduit is provided extending from the valve to the sides of the automobile. The ends of the conduit may be closed by a cap or by a valve when not in use and an auxiliary flexible hose, which preferably is insulated by heat lagging, is provided which may be connected onto one end of the tubing in any suitable manner, the flexible hose preferably carrying a nozzle of suitable construction at its other end which may be introduced through the water outlet of the fire hydrant. This nozzle may carry a plurality of fingers which hold the nozzle spaced from the wall of the hydrant so that the exhaust gas introduced into the hydrant may escape from the water conduit around the nozzle.

The invention will be described in greater detail with reference to the accompanying drawing

wherein I have diagrammatically illustrated a preferred embodiment for carrying out my method and wherein:

Figure 1 diagrammatically represents a motor truck and the connection between the exhaust line of the motor truck and a water hydrant, 5

Figure 2 shows the manner in which the hot gases are introduced into the hydrant casing and circulate through the casing, 10

Figure 3 diagrammatically represents the deflecting valve in open position, and 10

Figure 4 diagrammatically represents the deflecting valve in by pass position.

Referring to the drawing, the chassis of an automobile truck, diagrammatically shown, is represented by the numeral 1 and carries an internal combustion engine diagrammatically shown and indicated by the numeral 2. The engine 2 is of any suitable construction and may burn fuel oil, gasoline or gas, or other fuel. The exhaust from the cylinders of the motor 2 is conducted by a manifold 3 through the deflecting valve 4 to the muffler 5, from which the gas normally is conducted by the exhaust line 6 to the atmosphere. The deflecting valve 4 preferably 25 is a cylindrical or tapered plug valve and has a straightway passage 10 therethrough and deflecting passages 11 and 12 at an acute angle thereto, the passage 10 having a wide mouth 13. This arrangement provides a straightway connection at all times between the manifold 3 and muffler 5 except when the valve 4 is turned to by pass position to have passages 11 and 12 register with extensions 7 and 8. In by pass position shown in Figure 4, straightway passage 10 30 is connected by its flared end 13 with the exhaust manifold 3 and the down-stream end of the passage is closed, thus deflecting the exhaust gases by passages 11 and 12 into the extensions 7 and 8. The deflecting valve has tubular extensions 40 7 and 8 extending from the valve casing to the side of the truck which normally are closed by a cap 9 threaded on the end of the extension. A flexible insulated hose 14 of any suitable construction is adapted to be connected to the end 45 of the tube 7 or 8 and preferably carries a nozzle 15 at its other end adapted to be inserted into the nozzle 16 of the fire hydrant, and upon which is secured spring fingers 17 which hold the nozzle in spaced relation thereto.

50

The operation of my invention is as follows:

In order to thaw out the hydrant the motor 2 is started, one cap 9 is removed, the flexible hose 14 is connected to the extension 8 and the valve 8 is turned to proper position to direct the waste gases 55

into the extension 8 and hose 14. The nozzle 15 is inserted into the hose connection 16 of the water hydrant and is held in place by spring fingers 17 engaging the hose connection of the hydrant to direct the gases downward, and the hot gases are conducted into the casing of the hydrant and around the frozen valve.

As the gases will be at high temperature, the ice in the hydrant is rapidly melted. By opening the 10 valve of the hydrant it is not necessary to melt all the ice as the pressure of the water will break up the ice, and as soon as the water begins to flow through the hydrant the thawing nozzle is removed. The fire hose then is connected to the 15 hydrant and the flow of water will rapidly erode the ice until it is all melted. When a long nozzle extending to the bottom of the hydrant is employed, it is preferable to throttle the engine to prevent backfiring. When not in use, the flexible 20 hose 14 may be disconnected and carried on the truck.

It will be understood that various modifications of my invention may be made without departing from the spirit or scope thereof.

What I claim as my invention and desire to secure by Letters Patent is:

1. Means for thawing frozen water apparatus comprising a flexible hose connected at one end to an exhaust line of an internal combustion engine 5 on a vehicle and removably connected at the other end to the apparatus to be thawed to introduce heated gases therein in such manner that an escape path is provided at the connection whereby said exhaust gases may be freely circulated 10 through said apparatus.

2. Means for thawing a frozen water hydrant having a nozzle comprising a flexible hose connected at one end to an exhaust line of an internal combustion engine on a vehicle and removably 15 connected at the other end to the hydrant to be thawed by spacing fingers secured to said hose and adapted to engage the hydrant nozzle to introduce heated gases therein in such manner that an escape path is provided at the connection 20 whereby said exhaust gases may be freely circulated through said hydrant.

JAMES G. GRIFFITHS.
